[57] ABSTRACT

An improved convertible sofa bed which can be quickly and easily converted for day or night use; the device consisting of a frame that supports two bed springs, each with a separate mattress, a rear one of which is pivotable between a vertical and horizontal position so to serve as a back rest when converted into a sofa, or which at nighttime together with the sofa seat form a double bed.

SHEET 2 OF 2

CONVERTIBLE BED SOFA

This invention relates generally to convertible furniture.

A principle object of the present invention is to provide a convertible bed sofa which is of improved design so that it can be more readily changed between day and night uses.

Another object is to provide a convertible bed sofa which includes a storage space therebeneath for holding bed sheets, bed pillows and blankets during a day and which holds the sofa back rest pillows at night, so to eliminate need of extra closet space.

Still another object is to provide a convertible bed sofa which includes a removable arm rest tray that can serve either as a writing table, book rest, or support for dishes and drinking glasses to persons while seated on the sofa.

Other objects are to provide a convertible bed sofa which is simple in design, inexpensive to manufacture, rugged in construction, easy to use and efficient in operation.

These and other objects will be readily evident upon a study of the following specification and the accompanying drawing wherein:

FIG. 1 is a perspective view of the invention in position for use as a sofa, and shown with skirt and back rest cover added so to cover all metal bed frames.

FIG. 2 is a diagrammatic cross section on line 2—2 of FIG. 1.

FIG. 3 is a diagrammatic cross section similar to FIG. 2 and showing the invention made up as a bed.

FIG. 4 is a cross section in direction 4—4 of FIG. 2.

FIG. 5 is an enlarged cross section of details when the invention is in the position shown in FIG. 3.

FIG. 6 is a view of mechanism that is located at each end of the device.

FIG. 7 is a view of the push rod.

FIG. 8 is a view of one end of the seat frame.

FIG. 9 is a cross sectional view on line 9—9 of FIG. 6.

Referring now to the drawing in detail, the reference numeral 10 represents a convertible bed-sofa according to the present invention wherein there is a stationary frame 11 consisting of right and left side walls 12 and 13 interconnected by front and rear angle iron bars 14 and 15 respectively.

The frame 11 supports a rear and front bed-spring 16 and 17, each bed spring having a mattress 18 and 19 respectively.

Each of the side walls 12 and 13 includes a horizontal groove 20 in which a roller 21 of frame 17 is slidable. Also a roller 22 of frame 16 is slidable in the groove 20 when the frame is in a horizontal bed position. A notch 23 allows roller 22 to enter the groove 20 when the sofa bed is being assembled in a factory, as best shown in FIG. 6.

The frame 16 also includes a roller 24 at each end which is slidable in a groove 25, the groove being generally vertical with a slight upwardly rearward incline, in order that when the frame 16 is supported with roller 24 therein while roller 22 is at a rear end of groove 20, the back rest 26 thus formed thereby (as shown in FIG. 1) is comfortable for persons to lean against while the present invention is in the converted position of a sofa 27. The upper end of the groove 25 opens out on the upper edge 28 of each side wall 12. The upper edge 28 of each end wall 12 is fitted with a cover plate 29 so to

cover the upper end of groove 25 and notch 23, so to make a final finished and more pleasing appearance to the sofa 26.

It is to be noted that the mattress 18 is securely fastened to the frame 16 by means of hooks 30, permanently affixed to the mattress, and which hooks up with the wire mesh 31 of the frame, thus preventing the mattress to fall off the frame when the frame is in the slightly rearward tilted upright position shown in FIG. 2.

When the frame 16 is in the upright position of FIG. 2, the roller 24 is in a lower portion of groove 25. When the sofa is intended to be converted into a double bed 32, the frame 16 is pivoted forwardly above the roller 24 at each end of the frame, thus causing the rollers 24 to climb up into an upper portion of the grooves 25 in each side wall 12 and 13, and the rollers 22 at a same time thus traveling forwardly within the grooves 20, as shown in FIG. 3. When the frame 16 is thus forwardly pivoted to form the bed, the frame comes to a stop in a horizontal position by resting upon bracket 33 secured to each end wall 12 and 13. In order to prevent the frame 16 to accidentally start tipping from a horizontal to the vertical upright position when a sleeping person rolls over so that his weight is shifted over the rollers 24, a support structure 34 is provided to support rollers 24.

The support structure 34 in each end wall 12 and 13 includes a horizontal tubular sleeve 35 in which a metal rod 36 is slidable. A forward end of the rod has a knob 37 located adjacent a front edge 38 of the side wall so that it can be conveniently grasped by a person. A rear end of the rod is tapered to a point 39. The length of the rod is such so that when the knob is pushed in against the edge 38, the tapered end 39 is located directly under the roller 24 (as shown in FIG. 5) so that it rests thereupon, thus preventing accidental tilting of the frame 16 when in a bed position. When a person wishes to convert the present invention between a sofa and a bed, he simply pulls on knobs 37 so to pull rods 36 slightly forwardly, thus allowing the rollers 24 to be cleared by rod ends 39 so to move up or down the grooves 25, after which the knob is again pushed in so to be out of the way for being bumped against by a person's leg.

The frame 17 supporting mattress 18 forms a seat 40 for the invention when in a sofa position. When in use as a bed, the frame 17 is pulled forwardly, as shown in FIG. 3 so to allow space for the frame 16 to swing down to the above described horizontal position thereof. Frame 17 is easily moved forwardly, by means of its rear portion being supported on the rollers 21 while its front is supported upon a pair of legs 41 resting upon casters 42 for easy rolling across a floor. A guide roller 43 mounted near a front of the side wall prevents the frame rubbing against the side wall while being moved so that the operation is relatively friction free and effortless. When the frame 17 is pulled fully forward, to clear the frame 16, as shown in FIG. 3, the roller 22 abuts against a forward end of the groove 20. When the frame 17 is pushed in to form the sofa seat, a pair of hooks 44 pivoted on pins 45 of the legs 41 are swung downward so to hook around the angle iron bar 14 thus locking the frame so to prevent it to accidentally slide forward.

When in a sofa position, the frame 16 is prevented from accidentally tilting forwardly by means of a pair of

tension coil springs 46 secured at one end to the bar 14, and secured at their other end to frame 16, thus urging it against pivoting forwardly. A bracket 47 carrying a freely rotatable roller 48 guides the spring 46 across the top of the bar 15, as shown in FIGS. 2 and 6.

When used as a sofa, pillows 49 are placed against a front side of the upright frame 16 which is first covered by a slip cover 50 so to hide the metal framework of the frame 16 and the mattress 18. A slip cover 51 together with skirt 52 covers the mattress 19 and the metal work of frame 17 and legs 41. When not in use, pillows 49 fit under the bed, as shown in FIG. 3.

Each end wall 12 and 13 includes an arm rest 53 having vertical opening 54 therethrough aligned with opening 55 of cover plate 29 and opening 56 in the end wall so to removably receive a metal rod 57 secured to underside of a tray 58, that can serve as a table to hold papers, books, ash trays or food dishes and drinking glasses.

Thus a convertible bed sofa is provided.

While various changes may be made in the detail construction, it is understood that such changes will be within the spirit and scope of the present invention as is defined by the appended claims.

What is claimed is:

1. In a convertible bed sofa, the combination of a stationary frame comprised of opposite side walls and interconnecting front and rear angle iron bars, and a pair of bed frames supported thereupon, each said bed frame having a mattress thereupon, a first of said bed frames being adjustable to serve either as a back rest in a sofa position or as a rear bed member of a double bed

when in a bed position, while a second of said bed frame is adjustable to serve as a seat in said sofa position or as a front bed member in said bed position, each said end wall including a horizontal groove and a slightly inclined vertical groove, said first frame having a first roller in said horizontal groove and a second roller in said vertical groove, while a rear portion of said second frame is supported on a roller carried in said horizontal groove, a forward end of said second frame being supported on a pair of front legs mounted on casters, a forwardly slideable bar in each said end wall intercepting at its rear end said vertical groove so to support said first frame roller carried in said vertical groove, when in said bed position, said bar having a knob upon a front end which abuts with a front edge of said side wall when said rear end intercepts said vertical groove and said first frame vertical groove roller rests thereupon, said bar rear end being tapered to a point and said bar being slideable inside a tubular sleeve extending from said side wall front edge to said vertical groove.

2. The combination as set forth in claim 1, wherein said first frame is secured to said mattress by hook means.

3. The combination as set forth in claim 2 wherein said side walls each include an arm rest, each arm rest including a vertical single opening, said opening supporting a tray unit comprised of a horizontal tray mounted upon an upper end of a singular vertical rod receivable within said opening.
